UNITED STATES PATENT OFFICE.

HENRY C. WEEDEN, OF BOSTON, MASSACHUSETTS, ASSIGNOR TO THE WEEDEN SANITARY MANUFACTURING COMPANY, OF RHODE ISLAND.

AUTOMATIC FLUSHING DEVICE.

SPECIFICATION forming part of Letters Patent No. 416,141, dated November 26, 1889.

Application filed June 17, 1889. Serial No. 314,606. (No model.)

To all whom it may concern:

Be it known that I, HENRY C. WEEDEN, of Boston, in the county of Suffolk and State of Massachusetts, a citizen of the United States, 5 have invented certain new and useful Improvements in Automatic Flushing Devices, of which the following is a specification.

My invention relates to that class of apparatus in which the flushing of the bowl of 10 a urinal or similar structure is accomplished by means of the siphon action produced by the downward and outward passage through a pipe of suitable caliber of liquid introduced from without into the bowl.

15 In the accompanying drawing I have represented in elevation and section a device embodying my present invention in a convenient form.

In the drawing, A represents the bowl to 20 be flushed, B the flushing-pipe leading thereto, and C the tank or water-supply. Below the bowl I provide an outlet-pipe D, of suitable caliber, through which liquid poured into the bowl from without may pass out.

25 This pipe is provided with a back-air cut-off d, and an overflow or surplus waste-pipe E may also be provided, as shown. The function of the back-air cut-off, as is well known, is to prevent air passing into the pipe D to 30 supply the place of that driven out by the flow of liquid through the pipe.

In connection with the pipe D, and at a point on the sewer side of the back-air cut-off, I provide an air-pipe F, extending upwardly and terminating in a siphon within 35 the tank. A branch f of the long leg of this siphon leads into a water-tight chamber G, formed within the tank, with which chamber the flushing-pipe B communicates by means 40 of a water-way which is normally closed by a float-valve g. As the normal water-level in this chamber is that of the top of the water-way into the flushing-pipe B, it is obvious that the float-valve will normally 45 close it. The flushing-pipe B may also be provided at its upper end with a siphon, (shown at H,) although, as will be hereinafter pointed out, this last feature is not essential. When this siphon H is employed, and in order 50 to regulate the amount of water discharged by it, its mouth may be inclosed

within a chamber h, having a small orifice, this being a well-known device for this purpose.

The operation of the apparatus is as follows, the parts being represented in their normal condition: When liquid is introduced into the bowl from without, it passes down through the outlet-pipe D, displacing the air therefrom. This produces rarefaction of the air in the air-pipe F, thus setting its siphon in 55 operation. A portion of the water drawn off by the siphon is conducted through the branch f into the chamber G, where it rises to a height sufficient to float the valve g off its seat, 60 thereby opening the water-way from the chamber into the flushing-pipe B. The water in the chamber will then descend through this pipe to flush the bowl until the level of the water in the chamber has been drawn 65 down to that of the water-way, when the flow of water will cease and the valve g will be seated. As the supply of flushing-water thus obtained would ordinarily be insufficient, a permanent flush of greater amount may be 70 obtained by attaching a siphon H to the upper part of the flushing-pipe. The flow of water downwardly through the flushing-pipe will start the action of this siphon, which 75 will continue until the withdrawal of the water uncovers its mouth.

It is obvious that to prevent air being drawn in through the branch pipe f from the chamber G, when the air is rarefied in the pipe F, this branch pipe f should be provided with 85 a suitable back-air cut-off. For this purpose a flap-valve f' may be placed upon the mouth of the branch pipe f within the chamber.

I claim—

1. In an automatic flushing device for urinals and similar structures, the combination, with the bowl to be flushed, of a flushing-pipe extending therefrom to the flushing-tank, a water-tight chamber in the tank, a water-way from the flushing-pipe to the interior of 95 this chamber, a float-valve normally closing the said water-way, a waste-pipe below the bowl having a back-air cut-off therein, and an air-pipe leading from the waste-pipe on the sewer side of the air cut-off upwardly to 100 the tank and formed at its upper part into a siphon having its short leg communicating

with the water in the tank and having a branch of its long leg leading to the interior of the said chamber.

2. In a device of the character described, 5 the combination, with the bowl to be flushed, of a flushing-pipe extending therefrom to the flushing-tank, a water-tight chamber in the tank, a water-way from the flushing-pipe to the interior of this chamber, a float-valve 10 normally closing the said water-way, a siphon H, connected with the flushing-pipe and communicating with the water in the tank, a waste-pipe below the bowl having a back-air cut-off therein, and an air-pipe leading from

the waste-pipe on the sewer side of the air 15 cut-off upwardly to the tank and formed at its upper part into a siphon having its short leg communicating with the water in the tank and having a branch of its long leg leading to the interior of the said chamber. 20

In testimony whereof I have hereunto subscribed my name this 15th day of June, A.D. 1889.

HENRY C. WEEDEN.
